ATTORNEY

UNITED STATES PATENT OFFICE

HENRY HERMANI, OF BALTIMORE, MARYLAND, ASSIGNEE, BY MINNE ASSIGNMENTS,
TO AMERICAN CAN COMPANY, OF NEW YORK, N. Y., A CORPORATION OF NEW
JERSEY

KEY OPENING CAN

Application filed August 9, 1937, Serial No. 311,698. Renewed April 30, 1931.

This invention is an improvement in key opening cans, and more particularly in means for temporarily connecting the key to the can prior to use in the opening thereof.

5 In the usual construction of cans of this character, extraneous means is provided for holding the key to the can, as for instance a loop beneath which the key may be inserted, or a key seat formed in the cover.

10 One of the primary objects of the present invention is the provision of a key connection so arranged that until required for use the key is firmly held in place, but wherein the arrangement is such that when required for use, the key may be easily detached from the cover.

Another object is the provision of a holding means of a nature such that it may perform a double function in those cans provided with a vent opening, sealed after cooking, serving as a seal for the vent opening, as well as a holder for the key.

With these and other objects in view the invention consists in the construction and 25 novel combination of parts fully described hereinafter, illustrated in the accompanying drawing, and pointed out in the claims appended hereto, it being understood that various changes in the form, proportion, size 30 and minor details of construction within the scope of the claims, may be resorted to without departing from the spirit of the invention.

In the drawing:—

35 Fig. 1 is a perspective view of a can provided with the improved key holding means.

Fig. 2 is a partial vertical transverse section through the can, part of the key being 40 also shown in section.

45 Fig. 3 is a similar view showing the adaptation of the vent opening seal as a key holder.

In the embodiment of the invention shown in Figs. 1 and 2, the can comprises a cylindrical body 1, with the usual bottom 2, and a flanged cover 3 secured to the body in any suitable manner as by means of a double seam 4. The body is provided at its top with a collar 5 inset in the end of the can, and suitably held, 50 as for instance by annularly ribbing or bead-

ing the lapping edges of collar and body, as indicated at 6.

A rip strip 7 is set off by score lines between the bead 6 and the double seam 4, and the said strip is provided with a tongue indicated at 8 55 for convenience in removing the same.

The key is of usual construction, including a shank or body 9 and a loop shaped handle 10. The body of the key is slotted as shown at 11 over a length sufficient to receive the 60 tongue, and preferably the body is flattened from side to side at the slot as indicated at 12.

The key is also provided with an extension 13 beyond the slot, and this extension is provided with a solder receiving opening or perforation 14, in the present instance a substantially rectangular opening. The extension is also flattened as shown, so that when the key is properly placed, it will lie flat on the cover. 65

The key is held in place on the cover by 70 means of a drop of solder indicated at 15, which passes through the opening in the extension, and connects with the cover. The solder is the usual soft solder, and while it 75 firmly holds the key in place, flat on the can top, it enables easy removal of the key by pulling outward on the handle. Preferably the drop is headed on the outer face of the key as indicated at 16, to provide a smooth finish. 80

The provision of the solder and its arrangement with respect to the key enables a considerable leverage to be exerted by the key when the handle end is lifted, sufficient to strip the solder so that it will pass through 85 the opening, or to break the connection thereof with the cover. Should the key break, it will naturally break adjacent to the solder, so that it will not be so damaged as to prevent its use in removing the rip strip. 90

In Fig. 3, the improved key attachment is shown in connection with that type of can having a vent opening, which is sealed after processing or other packing operation. In this construction the can indicated generally 95 at 17 is essentially the same as that shown in Fig. 1, except that the cover 18 is provided with a vent opening 19. This opening is as before stated, sealed with a drop of solder when the container is ready for permanent sealing, and this drop of solder is made use 100

of to hold the key in place, serving the same purpose as the solder 15 in Fig. 2.

The key indicated generally at 20 is the same as that shown in Fig. 1, having the extension 21 provided with the solder receiving perforation or opening. The solder 22 may be applied, and the key placed thereover, a part of the still fluent solder being pressed up through the opening, and more solder added if necessary. Or the opening of the extension 5 may be placed over the vent opening and the vent may be sealed through the opening. In either case the solder serves the double function of sealing the vent opening, and connecting the key to the can.

It will be obvious that the point of solder connection between the key and container should be located as far away from the handle loop as possible in order to obtain the 10 maximum degree of leverage for disconnecting the key from the container by lifting up the handle part. For this reason, the solder connection is located at the extreme 15 end of the key shank. This location has other advantages. If the solder connection 20 should be too strong to permit ready disconnection, the key will break adjacent the solder connection and leave the handle, 25 shank, and slot intact for subsequent use on in the removal of the tearing or rip strip.

It is thought that the invention and many 30 of its attendant advantages will be understood from the foregoing description and it will be apparent that various changes may 35 be made in the form, construction and arrangement of the parts without departing from the spirit and scope of the invention or sacrificing all of its material advantages, the forms hereinbefore described being merely 40 preferred embodiments thereof.

What is claimed as new is:—

1. A key opening can having a vent opening in its top normally closed by a drop of solder, and a key having an auxiliary opening at the end remote from the handle and beyond the rip strip engaging slot through which auxiliary opening the solder passes to hold the key to the can.
2. In a key opening can, a can body having a rip strip defined by score lines, an end secured to said body and having a vent opening, an opening key having a solder receiving perforation, said vent opening and said perforation being adapted to register and to be filled with solder to seal said vent opening and to secure said key to said end.

Signed at Baltimore, State of Maryland,
this 5th day of August A. D. 1927.

HENRY HERMANI.
